CONTAINER AND MEANS FOR EXHAUSTING
AIR THEREFROMWayne D. Brandon, Glenview, Ill., assignor to
Baxter Laboratories, Inc., Glenview, Ill., a cor-
poration of Delaware

Application August 7, 1935, Serial No. 35,181

4 Claims. (Cl. 226—82)

This invention relates to a container and means or apparatus for exhausting air therefrom.

An object of the invention is to provide improved mechanism for exhausting air from a container, and more particularly a container adapted to hold sterile liquids. A further object is to provide a container having improved sealing means. Other specific objects and advantages will appear as the specification proceeds.

10 The invention is illustrated, in a preferred embodiment, by the accompanying drawings, in which—

Figure 1 is a view in elevation of a container embodying my invention and mechanism also embodying my invention for exhausting air from the container; Fig. 2, an enlarged detail sectional view, the section being taken as indicated at line 2 of Fig. 4; Fig. 3, an enlarged broken sectional view, the section being taken as indicated at line 3 of Fig. 1; Fig. 4, a side view in elevation, the view being taken as indicated at line 4 of Fig. 1; Fig. 5, a view similar to Fig. 2, but showing the valve in position for exhausting air from the container; Fig. 6, an adjustable mechanism for controlling the length of the operating rod; Fig. 7, an enlarged detailed sectional view, the section being taken as indicated at line 7 of Fig. 4; Fig. 8, a perspective view of the cap employed; Fig. 9, a perspective view of the metal sealing disk; Fig. 10, a perspective view of the flexible sealing disk; Fig. 11, a perspective view of the inner clamping ring; Fig. 12, a perspective view of the rubber plug; Fig. 13, a part sectional view showing the assembly of the cap, metal sealing disk, and flexible sealing disk on top of the inner clamping ring; and Fig. 14, a broken sectional view showing a modified form of bell member providing a seal about the entire bottle or container.

40 In the illustration given, A indicates exhausting mechanism for exhausting air from the container B.

The apparatus A may be of any suitable construction. In the illustration given, I provide a supporting board or table 10 provided with a perforation 11 through which extends an actuating rod 12. Below the table 10 is a pivotally supported treadle bar 13 to which the rod 12 is secured. If desired, a turnbuckle 14 may be secured within rod 12 to permit adjustment thereof.

50 Mounted upon table 10 is a metal standard 15 to which is clamped a fixed support or collar 16. The collar 16 supports a compression spring 17 tending to urge upwardly a frame 18.

55 The frame member 18 is equipped with two arms

19 and 20 having apertures therein receiving post 15. The arm 20 is provided with an extension 21 slidably receiving guide 22. The upper end of guide 22 is fixed to bracket 23 which is also apertured to receive the post 15 and which is provided with a clamping lever 24 for fixing bracket 23 to standard 15.

The actuating rod 12, which is connected to treadle member 13, extends through openings in frame 18 and is normally urged in an upward 10 direction by spring 25 which rests upon a flange 26 at the lower side of frame 18, and which engages a lug 27 which is fixed to rod 12. The rod 12 is provided with a pair of spaced stops 28 and 29 near its upper side, where it passes through 15 the horizontal flange 30, the stops being on opposite sides of the flange and cooperating with the flange to limit the downward and upward stroke of rod 12.

Secured to the upper end of rod 12 is an arm 31 20 which in turn is secured to a vertical spring controlled valve 32. As shown more clearly in Figs. 2 and 5, the valve rod 32 is adapted to reciprocate through the central bore of valve block 33. The lower portion of the valve rod 32 is provided with 25 a vertical passage 34 which extends through the lower end of the valve and communicates with a recess 35 which communicates with the atmosphere through passages 36. The upper end of passage 34 communicates with an annular recess 30 37 about rod 32.

Extending transversely across the block 32 is a 35 passage 38 and threadedly connected to the block so as to communicate with passage 38 are conduits 39 and 40. Conduit 39 communicates with a reduced pressure line in which a pump or other suitable means provides a reduction of pressure. Pipe 40 communicates, as will be described later, with the exhausting mechanism adapted to be brought in contact with the container. The passage 38 is adapted to be brought in contact not only with the annular passage 37 communicating with the passage 34, but also with an annular passage 41 which permits air to flow from pipe 40 through and into pipe 39 in the air exhausting 45 operation.

Frame 18 is also provided with a pair of forwardly extending arms 42 and 43. The upper arm 42 is recessed to receive the upper end of pressure bar 44. Secured to the forward end 50 of the lower arm 43 is a collar 45 adapted to receive adjustment screws 46. The adjustment screws, as shown more clearly in Figs. 3 and 7, engage a tubular supporting member 47 which is interiorly threaded to receive the lower 55

Operation

threaded end 48 of the pressure member. The lower end of pressure bar 44 is reduced at 49 and provided with a groove 50 to receive the end of a screw driver. Integrally formed with the tubular supporting member 47 is a horizontal flange 51 forming the top of the reduced pressure chamber. Secured to the plate 51 is a cylindrical member 52 which is provided on one side with a threaded opening 53. At its lower side, the cylindrical member 52 is recessed to receive a rubber seal 54, the seal being adapted to engage the portion of the container B just below its neck, as shown more clearly in Fig. 7.

The bell or reduced pressure chamber formed by the flange 51, cylinder 52 and seal 54 is connected to the reduced pressure line 40 by a flexible rubber tube 55, as shown more clearly in Fig. 1. The pipe 40 may be provided with a vacuum gauge 56 if desired. The lower portion of tube 55 is connected to a metal pipe 57 which, in turn, threadedly engages the opening 53 of cylinder 52.

The container B may be of any suitable type or size. In the illustration given, the bottle is provided with a neck 60 having ribs 61 extending therearound. A rubber plug 62 is seated within neck 60 and is preferably provided with a top annular flange 63 resting upon the top edge of the neck. The plug 62 is preferably provided with a pair of openings 64 and 65 of the shape illustrated in Fig. 7. If desired, a glass tube 66 may be extended through opening 65, the head 67 of the tube resting within the shallow recess at the upper side of opening 65.

After the plug 62 has been placed in position, I preferably secure an inner clamping ring 68 in the position shown in Fig. 7, the lower edge of the metal ring being clamped about the lower bead 61, while the upper flange 69 rests upon the ledge or lip 63 of plug 62. In this manner, the plug 62 is clamped in tight sealing position within neck 60.

I next place a thin flexible sealing disk 70 of rubber or other suitable material upon the top of plug 62 so that the edges of the disk rest upon the horizontal flange 69 of clamping ring 68. It will be observed that the sealing ring 70 is substantially co-extensive with the top portion of the rubber plug 62.

Over the flexible seal 70, I place a metal disk 71 which clamps the peripheral edge of the flexible member 70 firmly against the horizontal flange 69 of the inner ring 68. The metal cap 72 is then placed over the flexible seal 70 and the metal disk 71, as shown more clearly in Fig. 13, and the lower edge portions 73 are spun under the lower shoulder of inner ring 68. If desired, the cap 72 may be provided with a tear flap 74. The metal of cap 72 is preferably thin so that the user may grasp flap 74 and by exerting tension thereon, tear a strip of metal away along the side of the cap, thus permitting the cap to be removed. I have found the use of certain aluminum alloys satisfactory for the construction of the inner ring 68, disk 71 and cap 72, although it will be understood that other suitable metals may be used.

In the modification illustrated in Fig. 14, there is secured to the top flange 51 a depending elongated cylinder 52 which completely encloses the container B. The cylinder 52 is equipped at its lower end with a rubber seal 53 which engages the board or foundation 10 upon which the container B rests.

In the operation of the apparatus, the container B equipped with the rubber plug 62 and inner ring or sleeve 68, as shown more clearly in Fig. 7, is placed upon the table 10, with the movable member 52 supported a spaced distance thereabove, as shown more clearly in Fig. 1.

The operator depresses pedal 13 with his foot, thus drawing rod 12 downwardly. The spring 25 is heavier than compression spring 17 and therefore causes the frame 18 to move downwardly bringing the cylinder 52 and rubber seal 54 into engagement with the bottle. Immediately following the downward movement of the frame 18, rod 12 causes the valve stem 32 to move downwardly, thus bringing the groove 41 into alignment with the passage 38, as shown in Fig. 5. The pressure bar 44 engages the flexible rubber seal 70 at a point midway between the two openings 64 and 65. The passage 41 in valve stem 32, as shown more clearly in Fig. 5, connects pipe 40 with the reduced pressure line 39 through the passage 38 of block 33. Air from the interior of the bottle passes out through either or both of the openings of the plug, the rubber seal 70 rising to permit the escape of the air. When the air has been exhausted, to a sufficient degree, the operator releases the treadle 13 and the spring 25 first moves rod 12 to its initial position shown in Figs. 1 and 2, with the passage 38 communicating with the annular groove 37 and therethrough with the vertical passage 34 which communicates with the atmosphere through passages 36. Immediately thereafter, the spring 17 urges frame 18 upwardly to the original position shown in Fig. 1.

The container B may then be removed from the platform 10 and the disk 71 is placed upon the flexible sealing member 70, as indicated in Fig. 13. The cap 72 is now placed in the position shown in Fig. 13, and the lower edges thereof clamped about the lower edges of the inner ring or sleeve 68.

The operation of the modification shown in Fig. 14 is substantially the same as that heretofore described, the only difference in the result being that the entire chamber about the container B is partially evacuated rather than just that portion about the bottle neck.

The new device permits a sealing ring 70 to be employed which substantially covers the rubber plug, thus giving a complete and permanent seal. At the same time, a seal can be employed which extends over the horizontal flange of the sleeve 58. Also, by employing the inner sleeve 68 and metal disk 71, the sealing member 70 can be locked permanently in sealing position between the two metal members.

The sealing apparatus by enclosing the entire bottle neck or the entire bottle if desired, enables a sealing mechanism to be employed which substantially covers the top portion of the bottle neck, while at the same time no pressure is exerted by the sealing chamber members directly against the top edge of the bottle, thus avoiding injury thereto.

In the mechanism shown, the pressure bar 44 can be readily adjusted by inserting a screw driver within groove 50 and rotating member 48 to raise or lower the bar; or, if desired, the upper portion of bar 48 may be grasped and rotated by suitable tools. In this manner, the exhausting mechanism can be readily adapted for use with different sized bottles as well as with bottles having necks of varying diameters.

While in the foregoing description, I have described the container and apparatus for exhausting the same in detail, it will be understood that changes in construction can be extensively made without departing from the spirit of my invention.

The foregoing detailed description has been given for clearness of understanding only, and no unnecessary limitations should be understood therefrom, but the appended claims should be construed as broadly as permissible, in view of the prior art.

I claim:

1. In apparatus of the character set forth, a support for a container, a standard extending above said support, a frame movably mounted on said standard, spring means urging said frame toward raised position, a valve rod extending through said frame, means for depressing said valve rod, and a spring associated with said valve rod, said spring being stronger than said first-mentioned spring so as to bring about a movement of said frame downwardly before said valve rod is actuated the required distance, a sealing head carried by said frame and adapted to form an air-tight chamber about at least a portion of said container, and means connecting said head with a reduced pressure line.

2. In apparatus of the character set forth, a support for a container, a standard extending above said support, a frame member movably mounted on said standard, a spring normally urging said frame toward raised position, a reduced pressure head carried by said frame and adapted to form an air-tight chamber about at least a portion of said container when said frame is moved to lowered position, a valve communicating with a reduced pressure line, a conduit between said valve and said head, a rod for actuating said valve, and a compression spring between an abutment carried by said rod and said frame whereby downward movement of said rod causes said frame also to move downwardly, said last-mentioned spring being stronger than said first-mentioned spring so that when the rod is depressed, the frame moves downwardly to bring said head into operative position with respect to said container prior to the opening of said valve.

3. In apparatus of the character set forth, a support for a container, a standard extending

above said support, a frame member movably mounted on said standard, a spring normally urging said frame toward raised position, a reduced pressure head carried by said frame and adapted to form an air-tight chamber about at least a portion of said container when said frame is moved to lowered position, a valve communicating with a reduced pressure line, a conduit between said valve and said head, a rod for actuating said valve, and a compression spring between an abutment carried by said rod and said frame whereby downward movement of said rod causes said frame also to move downwardly, said last-mentioned spring being stronger than said first-mentioned spring so that when the rod is depressed, the frame moves downwardly to bring said head into operative position with respect to said container prior to the opening of said valve, said second-mentioned spring serving also to actuate said valve when said rod is released prior to the raising of said frame, thereby raising the pressure within said head to atmospheric.

4. In apparatus of the class set forth, a support for a container, a standard extending above said support, a frame member movably mounted on said standard, a spring normally urging said frame toward raised position, a reduced pressure head carried by said frame and adapted to form an airtight chamber about at least a portion of said container when said frame is moved to lowered position, a reduced pressure line communicating with said head, a valve controlling said reduced pressure line and being operable to establish communication with the atmosphere with respect to that portion of the pressure line leading to said head, a vertically movable member for actuating said valve, an abutment carried by said vertically movable member, and a compression spring between said abutment and said frame whereby downward movement of said member causes said frame also to move downwardly, said last-mentioned spring being stronger than said first-mentioned spring so that when said vertically movable member, after being depressed, is released, said last-mentioned spring actuates said valve to establish communication between the atmosphere and said head prior to the raising of said head.

WAYNE D. BRANDON.
